UNITED STATES PATENT OFFICE.

ELMER R. CLOWARD, OF PAYSON, UTAH.

PLURAL-FILAMENT ELECTRIC BULB.

Application filed June 22, 1925. Serial No. 38,760.

This invention relates to electric bulbs and particularly to those provided with plural filaments so that each successive filament may be burned following the burning out of the 5 first filament.

An object of the invention resides in providing a lamp construction with a plurality of independent filaments connected with independent terminals at one end and to a 10 common terminal at the other end.

A further object of the invention resides in providing a lamp construction having a plurality of independent filaments together with suitable means for successively interposing the filaments in the circuits as they 15 burn out.

The invention further includes the provision of an electric lamp having a plurality of filaments connected to a common terminal 20 the opposite ends of said filaments connected to independent terminals so that they may be independently placed in circuit, and the provision of manually operated means for independently interposing said filaments in 25 circuit so its new filament can be interpositioned in the circuit after the previously used filament has burned out.

The invention comprehends other objects and improvements in the details of construction and arrangement of parts which are more particularly pointed out in the following detailed description and in the claims directed to a preferred form of the invention, it being understood however, that various changes in the desired shape and arrangement of parts may be made without departing from the spirit or scope of the invention as herein set forth.

In the drawing forming part of this application:

Figure 1 illustrates in side elevation an improved lamp construction embodying the improvements of the present invention, the base of said lamp being shown in section.

Fig. 2 is an elevation of the lamp construction having the base shown in section which illustrates the application of the principle to a certain slightly different type of lamp construction.

Fig. 3 is a view similar to Fig. 2 showing the application of the invention to a still different type of lamp construction.

Fig. 4 is a bottom plan view of the lamp base of the lamp construction shown in Fig.

1, showing the single contact in the central 55 portion of the base.

Fig. 5 is a bottom view of the lamp base shown in the construction illustrated in Fig. 2, illustrating the two contacts on the bottom of the base.

Fig. 6 is a detail perspective view of the filaments mounted in the lamp illustrated in Fig. 1.

Referring particularly to Fig. 1, the numeral 1 indicates the vacuumized container 65 mounted in the cylindrical base 2 and which has the usual plug 3 in which are positioned a common lead-in wire 4 and independent lead-in wire 5 and 6 respectively for the pair of filaments 7 and 8 respectively. The 70 filaments 7 and 8 are each connected at one end of the lead-in wire 4 while the opposite ends are connected to the lead-in wires 5 and 6 which also form the support therefor so that the filaments may be independently 75 interposed in electric circuits. In the bottom portion of the base 2 is mounted a cylindrical sleeve member 9 constructed of suitable insulating material in which is mounted a metallic sleeve 10 having a threaded bore 80 which is in spaced relation with respect to the metallic sleeve 11 also mounted in sleeve 9 and which threadedly mounts the contact screw 12. Access is provided to the screw 12 through the opening 13 in the base 2. 85

The common lead-in wire 4 is electrically connected with the central contact 14 on the bottom of the base 2 of the lamp while the shell electrode 15 is electrically connected with the metallic sleeve 10 to which the lead-in wire 5 is connected. The lead-in wire 6 is electrically connected to the sleeve 11 and from this construction it will be seen that in the ordinary use of the lamp the filament 7 will be heated to incandescence 95 through the interposing of the contact 14 and the shell electrode 15 in a suitable electric circuit. When the filament 7 burns out, the screw 12 can be operated so that it may be threaded into the sleeve 10 which will 100 interpose the filament 8 into the electric circuit between the shell electrode 15 and contact 14. In this way a single lamp construction can be provided to have a double light so that the construction and operation 105 of electric lamps can be considerably reduced.

In the lamp construction illustrated in

Fig. 2, the same structural relation of the parts exists, but in this lamp construction a pair of contact terminals as indicated at 16 and 17 are used to form the circuit connections for the filaments in a suitable electric circuit instead of the single contact in shell electrode structure of the device illustrated in Fig. 1. These two types of lamps are of well known construction in the art and are particularly used in connection with automobile headlights and the like.

Figure 3 is a similar embodiment of the invention as shown wherein the same is applied to the usual screw lamp 8 as used in connection with lamps constructed for house lighting and other similar purposes. In this construction the lamp bulb or vacuumized container as illustrated at 18 which carries the usual base construction 19 including the screw contact shell 20 at the central contact point or electrode 21. Suitable filament supporting wires 22 are mounted on the upper end of the standard 23 forming part of the plug of the lamp and support a pair of filaments 24 and 25 respectively. The supporting wires 22 for the filaments are separated in their central portions so as not to have electrical connections with one another and mounted for support upon one another by the glass balls 26. A common lead-in wire 27 extends to one end of both filaments while independent lead-in wires 28 and 29 respectively are connected to the opposite ends of the filaments 24 and 25 respectively. The lead-in wire 28 is connected to the shell electrode 20 as illustrated, while the lead-in wire 29 is electrically connected to the metallic sleeve 30 in which is adjustably mounted the contact screw 31 adapted under manual operation for electrical contact with the metallic sleeve 32 which is in circuit with the electrode 20 so that after the filament 24 is burnt out, the screw 31 may be operated to place the filament 25 in the same circuit.

From the above description it will be seen that a highly novel and efficient lamp construction has been provided wherein a plurality of filaments may be supported and connected to a common lead-in wire while independent lead-in wires are connected to opposite ends of the filaments and a suitable contact mechanism so that they may be suc-

cessively interposed in circuit in any desired manner for use after other filaments have 55 burned out.

What is claimed as new is:

1. A lamp of the class described, comprising an evacuated container, a base mounted on said container having a pair of contact terminals thereon, a sleeve member formed of insulating material mounted in said base, a plurality of metallic sleeves mounted in relative spaced relation within said insulating sleeve, a movable contact member for engaging said metallic sleeves in a predetermined manner, a plurality of filaments supported in said evacuated container, a common electrical connection between one of the terminals on said lamp base and one end of 70 each of said filaments, and independent circuit connections between the opposite ends of said filaments and predetermined contact sleeves in said insulating sleeve, whereby the operation of the movable contact 75 members for engaging predetermined metallic sleeves will operate to interpose predetermined filaments in circuit between the opposite terminals on said lamp base in a predetermined manner.

2. An electric lamp, comprising an evacuated container, a base mounted on said container having a pair of contact terminals thereon, a sleeve member formed of insulating material mounted within the base and opening through one side thereof, a plurality of contact blocks mounted in said insulating sleeve in spaced relation and having alined openings formed therein, a contact member movably mounted in said contact block within the sleeve member and adapted to make and break an electric circuit between said blocks, and a plurality of filaments supported in said evacuated container having a common electrical connection with one of said blocks and terminals on said lamp base, having the opposite terminals electrically connected to predetermined other blocks in spaced relation, said movable contact member being adapted to control the electrical connection of the last named terminals of said filaments with the other contact terminal on the lamp base.

In testimony whereof I affix my signature.

ELMER R. CLOWARD.
